PNEUMATIC BALLAST TAMPER

Auguste Scheuchzer, Lausanne, Switzerland

Application December 7, 1950, Serial No. 199,616

Claims priority, application Switzerland
December 12, 1949

1. Claim. (Cl. 104—11)

1

My invention relates to an apparatus for conveying fine gravel to and compacting it within cavities under the sleepers of a railroad track by means of compressed air.

This apparatus comprises a fine gravel storage vessel having an aperture in a vertical side wall closed by a plate of transparent material carrying volumetric graduations adapted to allow the amount of fine gravel, effectively projected into the cavities under the sleepers to be checked with a practically sufficient accuracy.

A further object of the invention is to provide means by which the moist gravel particles running in the vicinity of the side walls of the ejecting nozzle will be submitted to a stronger dynamic air pressure than that acting upon the particles running in the central portion of the ejection nozzle connected to a conveying pipe fed by the storage vessel with fine gravel and compressed air, so that these particles can be efficiently loosened from the nozzle walls.

These, and other objects and advantages of this invention, will be clearly disclosed and described in the following specification, the accompanying drawings, and the appended claim.

A preferred embodiment of this invention is illustrated in the drawings, in which:

Fig. 1 shows in front elevation an apparatus comprising an air compressor on a truck.

Fig. 2 is a cross sectional view, through the vertical, longitudinal axis of symmetry of a sleeper and the axis of the gravel-storage vessel.

Fig. 3 is a cross sectional view at right angle to the sleeper and corresponding to Fig. 2.

Fig. 4 is a cross sectional view of the projection members taken from the plane IV—IV on Fig. 3.

The apparatus illustrated as a whole on Fig. 1 comprises a truck on rails with a carrying frame 1, on which are fixed a motor 2, an air compressor 3 driven by the motor and an air storage vessel R. A gravel-storage vessel 4, adapted to be set in operating position by a workman between the sleepers of the railway track, is provided with a double conveying pipe 5, to which is connected an ejection nozzle 6, a flexible air duct 7 connecting the air storage vessel R and the admission orifice 8 of the conveying pipe 5 for the admission of air into the latter.

The intermediary conveying pipe 5 is curved at a right angle as at 5' and has a vertical end portion 55 connected to the vessel bottom. This pipe comprises a large curved channel 9 for the gravel and a smaller, flat air channel 10 subdivided over a downstream part of its length with a medial longitudinal partition 11, which produces two flattened orifices separating the air

2

stream into two lateral jets which ensure optimum impulsion of the gravel, so that moist particles running in the vicinity of the side walls of the ejection nozzle 6, will be efficiently loosened from the side walls, being submitted to a stronger dynamic air pressure than that acting upon the particles running in the central portion of the ejection nozzle.

The air channel 10, the upper end of which 10 is provided with the inlet orifice 8, is used for the injection of the compressed air. The threaded orifice 8 carries a valve 12, controlling the output of compressed air. At its lower end, the channel 10 emerges, just below the outlet orifice of the gravel channel 9, into the interchangeable ejection nozzle 6, frictionally held on the pipe 5.

The gravel-storage vessel 4 has an aperture 54 in a vertical side wall 56 thereof, closed by a plate 27 of transparent material carrying volumetric graduations v, enabling the operator to check the amount of fine gravel stuffed in the hole H, under the raised sleeper 13 illustrated in Fig. 2. The reference numeral 14 denotes a rail resting on the sleeper 13.

The ejection nozzle 6 comprises an inlet mouth 40, connected to the outlet opening of the conveying pipe 5, and is provided with a horizontal straight first flat portion 41 followed by a second portion 42 curved substantially at right angle in a horizontal plane. This second portion 42 comprises an ejecting orifice 43 adapted to direct the fine gravel G in the hole H lengthwise with respect to a raised sleeper 13, after the ejection nozzle has been introduced under a lateral side of said sleeper (see Fig. 3).

In order to render possible the introduction of the nozzle 6 under the sleeper previously raised up to its correct level, it is only necessary to remove a little of the ballast B towards the middle of the sleeper. The fine gravel injected in the longitudinal direction fills the hole H, and it is retained at the end and at the sides by the ballast which is already there.

From Fig. 2 it appears that the main portion of the ejection nozzle 6 itself constitutes a barrier preventing the projected fine gravel G from reaching the middle portion of the hole H below the sleeper. After filling up with fine gravel the first lateral portion of this hole, located between the ejecting orifice 43 and the left end 13' of the sleeper 13, the ejection nozzle 6 is carefully withdrawn from the said hole; however, as a matter of fact, the fine gravel G, strongly tightened, will not be submitted to an injurious decompression towards the middle of hole H by that removal of the nozzle 6.

Then the workman takes the apparatus to the other side of the sleeper 13, turns it over 180° about a vertical axis and again introduces the main portion of the ejection nozzle 6 in the middle part of the hole H, so that the projection of fine gravel in the said hole is carried out in the direction of the arrow F₁ (see Fig. 2) towards the right-hand end, not shown, of the sleeper 13.

What I claim is:

Apparatus for conveying fine gravel to and compacting it within cavities under the sleepers of a railroad track by means of compressed air, comprising in combination, a fine gravel storage vessel having an aperture in a vertical side wall closed by a plate of transparent material carrying volumetric graduations, said storage vessel having an opened bottom, an intermediary conveying pipe curved at a right angle and having an inlet vertical end portion connected to said vessel bottom and an outlet opening, a flat air channel secured to said conveying pipe provided with an inlet aperture and with a vertical medial longitudinal partition over a downstream part of its length so

as to form at its outlet end two horizontally juxtaposed flattened orifices arranged underneath said outlet opening of the conveying pipe over the whole width of said latter opening, an ejection nozzle having an inlet mouth connected to said outlet opening and said two flattened orifices, said ejection nozzle being provided with a horizontal straight flat first portion followed by a second portion curved substantially at a right angle in a horizontal plane, said second portion being provided with an ejecting orifice adapted to direct the fine gravel lengthwise with respect to a raised sleeper, after the ejection nozzle has been introduced under a lateral side of said sleeper.

AUGUSTE SCHEUCHZER.
